(57) **CLAIM**

The ornamental design for a printer, as shown and described.

DESCRIPTION

FIG. 1 a front view of a printer;

FIG. 2 is a top view thereof;

FIG. 3 is a right-side view thereof;

FIG. 4 is a left-side view thereof;

FIG. 5 is a rear view thereof;

FIG. 6 is a bottom view thereof;

FIG. 7 is a perspective view thereof;

FIG. 8 is a perspective view with a handset removed;

FIG. 9 is a perspective view with a document tray in an open position;

FIG. 10 is a perspective view with a paper cassette removed; and,

FIG. 11 is a right-side view similar to FIG. 3 with a stand in a withdrawn position.

The broken lines are for illustrative purposes only and form no part of the claimed design.
